UNITED STATES PATENT OFFICE.

GEORGE W. LEIMAN, OF NEWARK, NEW JERSEY, ASSIGNOR TO LEIMAN BROS., OF NEW YORK, N. Y., A COPARTNERSHIP COMPOSED OF WILLIAM H. LEIMAN, GEORGE W. LEIMAN, GUSTAVE A. LEIMAN, EDWARD C. LEIMAN, AND JOHN LEIMAN.

LIQUID-DISPENSING DEVICE.

Application filed January 11, 1922. Serial No. 528,570.

This invention relates to liquid dispensing devices, and more particularly to a device for delivering predetermined quantities of liquid as for instance, supplying lubricating oil to various parts of machines, whereby the amounts discharged may be varied.

Another object is to provide a device having a plurality of discharge outlets, each of 10 said outlets being adapted to be independently oscillated to control the amount of liquid to be discharged therefrom.

Another object is to provide a device having a common reservoir for the liquid 15 in open communication with the plurality of discharge outlets.

Another object is to provide a device having means interposed between the reservoir and the discharge outlets for opening and 20 closing communication therebetween.

Another object is to provide certain improvements in the form, construction and arrangement of the several parts whereby the above named and other objects may be 25 effectively attained.

A practical embodiment of my invention is represented in the accompanying drawings, in which—

Fig. 1 represents a plan view of my improved device with certain parts removed, 30 the outline of which parts being shown in dotted lines.

Fig. 2 represents a detail vertical section taken in the plane of the line II—II of 35 Fig. 1.

Fig. 3 represents a front elevation, certain of said parts being broken away to show other portions more clearly.

Fig. 4 represents a detail vertical section 40 taken in the plane of the line IV—IV of Fig. 3, and

Fig. 5 represents a perspective view of one of the yielding washers interposed between the nozzles.

The frame of the device is denoted by 1 and comprises a platform 2 having an annular rim 3 and ears 4, a reservoir 5 extending laterally from the platform and a depressed passage 6 which leads from the 50 platform to the reservoir. A chamber 7 is located in the frame below the reservoir and has communication therewith through a hole 8 in the bottom of the reservoir.

Tubular members 9 are held in screw threaded engagement with the frame 1 and 55 in open communication with the chamber 7. The outer end of each member 9 is also screw threaded to receive a thumb nut 10. The members 9 are provided with a longitudinally arranged slot 11 forming a common port, the function of which will be hereinafter explained. Discharging nozzles are mounted on the tubular members 9, each of which nozzles consists of a body portion 12 and a curved tube 13. The body portion is provided with an interior annular channel 14 which connects with the tube 13. The body portions 12 are mounted on the tubular member 9 so as to be oscillated independently. A washer 15 of leather, or 60 other suitable yielding material, is located between each of the body portions and the thumb nut 10, which nut is arranged to be manipulated so as to exert pressure on the washers and body portions between the 65 frame and nut, thereby forming a liquid tight seal between the body portions. To prevent the movement of one nozzle being transferred to an adjacent nozzle through the washers 15, I provide each of the washers with an integral projection 16 which extends into the longitudinal slot 11, as shown in Figs. 3 and 4, and holds the washers 70 against rotation.

A liquid container 17 of glass, or other 75 suitable material, closed at the top, is provided with a bottom 18 having an upwardly extending edge 19 which is secured to the container.

The bottom 18 has an opening 20 forming a port arranged to register with the passage 6, which opening may be closed by a plate member 21 pivoted at 22 to the bottom 18. This plate member 21 is provided with a slot 23 forming a port having depending walls 24 which enter the passage 6 and secure the member 21 against rotation. The container is removably secured in position on the platform 2 by means of oppositely disposed pins 25 which extend laterally from the edge 19 of the bottom 18 and are arranged to enter recesses 26 in the rims 3. Thus it will be seen that by the container being inverted it may be filled with liquid through the opening 20 which is 100 closed by rotating the plate member 21. 105

The container is returned to its position on the platform with the depending walls 24 located in the passage 6 and rotated on the pivot 22 so as to cause the pins 25 to enter the recesses 26, thereby holding the container securely in place on the platform. When the pins 25 are positioned in the recesses, the opening 20 will register with the slot 23 in the member 21 and the liquid free to 10 pass into the passage 6 through to the reservoir 5.

To prevent the liquid from flowing through the nozzles, I provide a conical valve 27 which is arranged to seat in the hole 8 in the bottom of the reservoir. This valve is hinged at 28 to a lever 29 pivoted at 30 in brackets 31 fixed on the frame 1, which lever is provided with a handle 32 for manually operating the valve. Connections (not shown) may be made with the handle, whereby the valve may be mechanically operated.

When the container is located in position on the platform with the opening 20 in register with the slot 23 of the plate member 21, the liquid will flow downwardly until the reservoir is filled to a level which alines with the opening 20, and as the valve 27 is lifted from the hole 8 in the bottom of the reservoir, the liquid will flow into the chamber 7, tubular members 9, through the slots 11, into the annular channels 14 of the body portions, and be discharged through the tubes 13. To receive the discharged liquid 35 from the tubes, I provide a series of hoppers 33 each having a feed pipe 34 which may be led away from the device and so convey the liquid to be used as desired. To support the hoppers and feed pipes in position, and to 40 inclose the nozzles to exclude dust and dirt, a box 35 is secured to the frame 1 by screws 36. The box 35 is provided with a door 37 hinged at 38 to the bottom of the box, and a locking device 39 is secured at the top of 45 the box for holding the door in a closed position.

The amount of liquid discharged from the tubes is controlled and maintained by the 50 position the tubes 13 assume with respect to the level of the liquid in the reservoir when the valve 27 is open. For instance, if the discharge end of the tube is above the level of the liquid in the reservoir, the liquid will be cut off entirely, as shown in dotted lines 55 in Fig. 4. When the mouth of the tube is level with the liquid in the reservoir, only a small quantity will pass from the tube. The lower the mouth of the tube is brought 60 below the level of the liquid in the reservoir, the greater the quantity of liquid will be discharged therefrom.

It is evident that various changes may be resorted to in the form, construction and 65 arrangement of the various parts without departing from the spirit and scope of my

invention; hence, I do not intend to be limited to the specific details herein described except as they may be included in the claims. What I claim is:

1. A dispensing device comprising a reservoir, a tubular member extending laterally therefrom, said member having a common port, discharging nozzles mounted on said member, said nozzles being arranged to be oscillated with respect to the level of the liquid in the reservoir to control the amount of liquid discharged therefrom, all of said nozzles being provided with interior channels in open communication with said common port. 70

2. A dispensing device comprising a reservoir, a horizontally disposed tubular member extending laterally therefrom, discharging nozzles mounted on said member and arranged to be oscillated vertically to control the amount of liquid discharged therefrom, and means for frictionally holding the nozzles in position on the member including yielding washers on the member located between the nozzles for forming a liquid tight 85 seal therebetween. 90

3. A dispensing device comprising a reservoir, a tubular member extending laterally therefrom, discharging nozzles mounted on said member and arranged to be oscillated to control the amount of liquid discharged therefrom, yielding washers on the member located between the nozzles for forming a liquid tight seal therebetween, 95 said member being provided with means 100 having a screw threaded engagement with the member and adapted to frictionally engage the outer nozzle to hold the nozzles in position on the member. 100

4. A dispensing device comprising a frame having a reservoir therein, a liquid container removably secured to said frame in position to connect with said reservoir, and an oscillatable means movable in a horizontal plane for opening and closing the 105 supply of liquid to the reservoir. 110

5. A dispensing device comprising a frame having a reservoir therein, a liquid container removably secured to said frame in position to connect with said reservoir, 115 and an oscillatable means movable in a horizontal plane on the container for opening and closing the supply of liquid to the reservoir. 120

6. A dispensing device comprising a frame having a reservoir therein, a liquid container removably secured to said frame, said container having a port arranged to be moved in a horizontal plane into and out of communication with the reservoir. 125

7. A dispensing device comprising a frame having a reservoir therein, a liquid container removably secured to said frame, said container having a port arranged to be moved in a horizontal plane into and out of 130

communication with the reservoir, and means for closing said port. and out of alignment to open and close communication between the container and reservoir.

8. A dispensing device comprising a frame having a reservoir therein, a liquid container removably secured to said frame, said container provided with horizontally disposed movable and stationary members having ports arranged to be brought into

In testimony, that I claim the foregoing as my invention, I have signed my name this 7th day of January, 1922.

GEORGE W. LEIMAN.
